ATTACHMENT FOR REVERSIBLE DOBBY HEADS

Filed July 22, 1929

UNITED STATES PATENT OFFICE

WILLIAM M. WATTIE, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS

ATTACHMENT FOR REVERSIBLE DOBBY HEADS

Application filed July 22, 1929. Serial No. 380,112.

This invention relates to a reversible doby head of the type in which the vibrator levers have three separate positions; high, low and intermediate. Such a doby is shown in the prior patent to Hussey and Stebbins, No. 1,691,156, issued November 13, 1928.

In such reversible heads, it is necessary that the vibrator levers be maintained in intermediate position at all times except when they are about to be raised or lowered. It frequently happens that a doby will contain extra vibrator levers in excess of the number of harnesses in use for a particular fabric. 10 In order to maintain such extra levers in intermediate or neutral position, it has been necessary to provide intermediate pattern links for each such extra vibrator lever throughout the length of the pattern chain. 15 It is the object of my invention to provide a simple attachment by which an extra vibrator lever may be maintained in intermediate position without the necessity of providing pattern chain links therefor. 20

In the preferred form, my invention consists in the provision of a series of removable supporting members which may be conveniently inserted in the doby whenever extra levers are to be rendered inoperative. 25

My invention further relates to arrangements and combinations of parts which will be hereinafter described and more particularly pointed out in the appended claims. 30

A preferred form of the invention is shown 35 in the drawings in which

Fig. 1 is a side elevation of a reversible doby head;

Fig. 2 is an enlarged side elevation of certain parts; and

Fig. 3 is a detail sectional view, taken substantially along the line 3—3 in Fig. 1.

Referring to the drawings, I have shown a portion of a loom frame 10 on which a doby frame 12 is mounted. A plurality of 45 vibrator levers 14 are pivoted at 15 in the

frame 12 and support vibrator gears 16 which are pivoted at 17 on said levers.

Links 18 are pivoted at 19 to the vibrator gears 16 and are also pivotally connected to the harness levers or jacks 20. Each vibrator 50 gear 16 is provided with a segmental slot 22, into which extends a lug or projection 24 on the vibrator lever. This projection 24 alternately engages the opposite ends of the segmental slot 22 and thus limits angular movement thereof to substantially a half revolution. 55 Driving or cylinder gears 24 and 26 are mounted in the frame 12 and are continuously rotated by suitable driving mechanism, not shown.

Each vibrator lever is provided with a roll 30 engaging the links of a pattern chain 32. The chain 32 is provided with high, low and intermediate links by which the vibrator levers are positioned to engage the upper or 60 lower cylinder gears or are held in intermediate or neutral position.

It will be obvious that the vibrator gears can make only a half revolution in a given direction and that any further movement 70 thereof must be a half revolution in the opposite direction. If the vibrator gear is left in its raised position during two successive revolutions of the upper cylinder gear 24, it will be obvious that the cylinder gear will 75 engage the teeth of the vibrator gear on its second revolution, but will be unable to rotate the gear further in the same direction. Consequently, breakage of parts will usually follow. The same situation arises if a vibrator 80 lever and gear are maintained in lowered position for two successive revolutions.

It is necessary, therefore, that all inactive levers be maintained in intermediate or neutral position. This is accomplished with 85 the regular or working levers by providing links 40 of intermediate height, by which the levers are held in the position shown in Fig. 1. Where extra levers are to be maintained inoperative for an indefinite period, I 90

provide an attachment which avoids the necessity of building up a long and heavy chain of intermediate links for each such lever.

My improved attachment comprises a series of supporting members 50, provided with hub portions 51 and set screws 52. These members 50 are conveniently mounted upon the rock shaft 54 which supports the usual lock bar 55 by which the vibrator levers 14 are held in high, low or intermediate position during the beating up of the weft.

The rock shaft is commonly moved angularly by a cam 56 which engages a cam follower 57 on an arm 58 secured on the rock shaft 54. A spring 59 (Fig. 1) causes the cam follower 57 to firmly engage the cam 56 and moves the rock shaft to the inoperative position shown in full lines in Fig. 2.

When it is desired to render a number of the levers 14 inoperative, the rock shaft 54 is pulled partially out of the frame 12, so that a desired number of supporting members 50 may be placed on the shaft. The parts are then re-assembled and the members 50 are secured to the rock shaft by the set screws 52 in such position that they will engage and support the selected vibrator levers 14, holding them in intermediate or neutral position. The slight rocking movement of the shaft 54 does not interfere with the effective support of the levers 14 by the members 50.

By the simple provision of the members 50 I avoid the necessity of building up a long and heavy pattern chain to maintain the extra levers in neutral position.

Having thus described my invention and the advantages thereof, I do not wish to be limited to the details herein disclosed, otherwise than as set forth in the claims, but what

40 I claim is:—

45 1. In a dobby head, a plurality of vibrator levers, pattern means to support said levers in high, low and intermediate positions, and additional devices by which selected levers may be supported in intermediate position, said devices being removably mounted in said dobby head.

50 2. In a dobby head, a plurality of vibrator levers, pattern means to support said levers in high, low and intermediate positions, a plurality of supporting members each effective to support a selected vibrator lever in intermediate position, and means to detachably secure said members in operative position.

55 3. In a dobby head, a plurality of vibrator levers, pattern means to support said levers in high, low and intermediate positions, a lock bar, means including a rock shaft for positioning said bar, and a plurality of supporting members detachably secured to said rock shaft and positioned to support selected vibrator levers in intermediate position.

60 4. In a dobby head, a plurality of vibrator levers, pattern means to support said levers in

high, low and intermediate positions, a locking bar for said levers movable to operative and inoperative positions, and means additional to said pattern means and to said locking bar effective to hold selected levers in intermediate position when said pattern means and said locking bar are both inoperative with respect to said levers.

65 In testimony whereof I have hereunto affixed my signature.

70 WILLIAM M. WATTIE.
